(57) **CLAIM**

The ornamental design for a rattle, as shown and described.

DESCRIPTION

FIG. 1 is a perspective view of a rattle in accordance with my invention thereof;

FIG. 2 is a front elevational view thereof, the rear elevational view being a mirror image of the front elevational view;

FIG. 3 is a right side elevational view thereof, the left side elevational view being a mirror image except for the rimmed disk surface as shown in FIG. 1;

FIG. 4 is a top plan view thereof; and,

FIG. 5 is a bottom plan view thereof.
